PROCESS TO PRODUCE FROM BAST FIBRE MATERIAL TECHNICAL FIBRES SUITABLE TO BE IMMEDIATELY WORKED UP INTO FIRST SLIVER

Hendrik Johannes Selling, Delft, and Cornelis Bok, The Hague, Netherlands, assignors, by mesne assignments, to Novivlas N.V., Delft, Netherlands, a limited liability company of Netherlands

Application February 5, 1954, Serial No. 408,550

Claims priority, application Netherlands February 7, 1953

2 Claims. (Cl. 19—29)

The invention relates to a process for converting bast fibre stalks into technical fibres, suitable to be immediately converted into first sliver. The process according to the invention is particularly suitable for the treatment of flax, both grades of which, viz. the retted flax and the unretted or green one, lend themselves excellently to this purpose.

As is known, bast fibre material, whether retted or not, is substantially subjected to the following treatments in order to achieve a form suitable for spinning. The dry material is first led through a braking apparatus, in which the woody core of the stalks is broken and substantially removed. The removal of the residual woody parts, the splitting of the coherent bundles of fibre into so-called technical fibres, the carding and the removal of short technical fibres, take place subsequently in a hackling apparatus. Finally the long technical fibres are combined to first sliver which can be spun.

The outlined procedure is laborious, since the feeding of the braking and hackling apparatus and of the apparatus for making the first sliver, as also the transport of the material between the apparatuses, is carried out manually. Another drawback is that as a result of the manual feeding of the said apparatuses the quantity of material treated per unit of time is subject to fluctuations, so that both the production capacity of the apparatus and the quality of the product obtained remain below the possible optimum. As a third drawback may be mentioned the necessity of storage between the separate treatments in order to prevent stagnation.

The object of the present invention is to obviate the drawbacks outlined above. It consists in a process for converting bast fibre stalks—with the application of a braking and hackling treatment known per se—into technical fibres, suitable to be immediately worked up into first sliver—by a treatment known per se also—which process is characterized in that the bast fibre stalks are supplied to the braking apparatus by means of any suitable dosing apparatus, in quantities which are constant per time unit, and that between the apparatuses in which the treatments outlined above are carried out, automatic means of transport are present, which supply the material from one apparatus to the other without storage.

As a result, the treatments preceding the spinning are combined into an organic whole, the components of which are adjusted to one another in their production capacity and to which the quantity of material is automatically supplied per unit of time to obtain the production and quality desired.

The invention is further illustrated by way of example in the accompanying drawing, representing schematically a top view of a possible arrangement.

In the drawing, reference numerals 1, 2 and 3 represent a dosing, a braking and a hackling apparatus re-

2

spectively. Automatic transport means 5 and 6 are located between these apparatuses, and automatic transport means 7 are positioned behind the hackling apparatus to deliver the fibres to an apparatus for producing first sliver, not shown in the drawing. Reference number 8 indicates a stock of stalks replenished by hand. From this stock the dosing apparatus forms the bundles 9, lying side by side. These bundles are conveyed to the braking apparatus by automatic transport means 5, and pass longitudinally through said braking apparatus as bundles 10, positioned in line with one another. The bundles of broken material leave apparatus 2 and enter automatic transport means 6, in which the material will form bundles 4 located side by side or even partly overlapping. After 15 subsequently having passed through hackling apparatus 3 the fibre material is caught by transport means 7, which convey it to the apparatus for forming first sliver.

Other arrangements are of course possible without departing from the scope of the invention.

We claim:

1. Method for converting bast fibre stalks into industrial fibres suitable to be immediately converted into first sliver, comprising the steps of automatically and periodically laterally separating from an irregularly supplied stock of bast fibre having stalks substantially lying side by side bundles of stalks of substantially uniform weight having stalks substantially lying side by side, continuously shifting said separated bundles laterally to the entrance of a braking apparatus, automatically and continuously feeding the bundles in the longitudinal direction of the stalks into a braking apparatus so that a continuous flow of stalks is broken in the braking apparatus, automatically and continuously transporting the broken stalks from the braking apparatus and delivering them laterally substantially lying side by side into a hackling apparatus wherein the stalks are hackled into industrial fibres suitable for being immediately worked up into a first sliver and supplying said fibres to the apparatus for forming the first sliver.
2. Method for converting bast fibre stalks into industrial fibres suitable to be immediately converted into first sliver, comprising the steps of automatically and periodically laterally separating from an irregularly supplied stock of bast fibre having stalks substantially lying side by side bundles of stalks of substantially uniform weight having stalks substantially lying side by side, continuously shifting said separated bundles laterally to the entrance of a braking apparatus, automatically and continuously feeding a plurality of the bundles in the longitudinal direction of the stalks into a braking apparatus so that a continuous flow of stalks is broken in the braking apparatus, automatically and continuously transporting the broken stalks from the braking apparatus and delivering them laterally substantially lying side by side in partly overlapped bundles into a hackling apparatus wherein the stalks are hackled into industrial fibres suitable for being immediately worked up into a first sliver and supplying said fibres to the apparatus for forming the first sliver.
